UNITED STATES PATENT OFFICE.

MILO TOTTEN, OF ABILENE, TEXAS, ASSIGNOR OF ONE-HALF TO A. H. KIRBY, OF ABILENE, TEXAS.

WIRE-HANDLING TOOL.

932,650.

Specification of Letters Patent. Patented Aug. 31, 1909.

Application filed January 2, 1909. Serial No. 470,289.

To all whom it may concern:

Be it known that I, MILO TOTTEN, a citizen of the United States, residing at Abilene, in the county of Taylor and State of Texas, have invented certain new and useful Improvements in Wire-Handling Tools, of which the following is a specification.

My invention relates more particularly to tools for stretching wire netting, so that it 10 may be secured to a frame.

Another object of my invention is to provide a tool for stretching wire netting which can be used for turning the edge of the netting over so that it may be securely fastened 15 after the netting has been stretched, and one which can be used on wide or narrow strips by a single adjustment of the claws.

Still another object of my invention is to provide a device of the character described 20 which will be strong, durable, efficient and simple and also one in which the several parts will not be liable to get out of order.

With the above and other objects in view, my invention has particular relation to cer- 25 tain novel features of construction and operation, an example of which is described in the following specification and illustrated in the accompanying drawing, wherein:

Figure 1 is a side elevation of my device, 30 showing the claws engaged with a piece of wire netting, Fig. 2 is a section of the handle of my device taken on the line $x-x$ of Fig. 1, and Fig. 3 is an end view of the tool. Fig. 4 is a section of the handle showing 35 how it may be used for lapping the wire.

In the drawings the numeral 1 designates a hollow handle which terminates in a head 2 adapted to be placed against a frame 3 while the claws 4 fixed on the threaded stem 40 5 are arranged to engage with the wire netting 6. In stretching wire screening, the

claws are fastened in the wire 6 as shown in Fig. 1, the frame being used as a fulcrum. Power enough to stretch the wire may be applied to the handle and the wire thus held 45 in position, may be readily attached to the frame. The claws may be adjusted to reach over a wide or narrow strip and engage with the wire by turning the threaded stem in or out of the head.

After the wire has been secured to the frame the rough edges of the same may be lapped back by inserting the rounded end of the handle under the edge of the wire and pushing the tool along the surface of the 55 frame, as shown in the section Fig. 4.

What I claim, is:

1. In a tool for stretching wire, the combination with a head, of a handle connected with the head, claws carried by the head, and 60 means for adjusting the claws.

2. In a tool for stretching wire netting, the combination with a head, of a handle fixed on the head, and adjustable claws carried by the head.

3. In a tool for handling wire netting, the combination with a head, of a handle having a concave lower side adapted to be used in turning the edge of the netting, and adjustable claws carried by the head.

4. In a tool for stretching wire netting, the combination with a head, of a handle carried by the head, a means adapted to engage with the wire carried by the head, and means for adjusting the last named means.

In testimony whereof I have signed my name to this specification in the presence of two subscribing witnesses.

MILO TOTTEN.
